(57) **CLAIM**

The ornamental design for a chaise lounge as shown and described.

DESCRIPTION

FIG. 1 is a front perspective view of a chaise lounge showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof; and,

FIG. 7 is a bottom view thereof.

The broken lines represent portions of the chaise lounge that form no part of the claimed design.
